UNITED STATES PATENT OFFICE.

LOUIS BEEZER AND MICHAEL J. BEEZER, OF PITTSBURG, PENNSYLVANIA.

CONCRETE RAILWAY-TIE.

SPECIFICATION forming part of Letters Patent No. 761,647, dated June 7, 1904.

Application filed June 8, 1903. Serial No. 160,451. (No model.)

To all whom it may concern:

Be it known that we, LOUIS BEEZER and MICHAEL J. BEEZER, citizens of the United States, residing at Pittsburg, in the county of Allegheny and State of Pennsylvania, have invented or discovered new and useful Improvements in Concrete Railway-Ties, of which the following is a specification.

In the accompanying drawings, which make part of this specification, Figure 1 is a plan of a tie constructed in accordance with our invention. Fig. 2 is a longitudinal section on the line 2 2 of Fig. 1. Fig. 3 is a cross-section on the line 3 3 of Fig. 1.

Our invention relates to railway appliances, and more particularly to railway-ties and rail-fastening devices.

It is the object of our invention to provide a substitute for the common wooden ties, which, owing to the scarcity of suitable wood and their increasing cost, must give way to an article cheaper to maintain. We have devised a tie which is not only cheaper, but one which is practically indestructible. Our tie, being thoroughly waterproofed, is fireproof in all its material parts, will not be affected by frost or water, and the parts are so strongly united that they will not become broken or separated. We also give the rails a suitable elastic bed which not only makes the trains less noisy and less injurious to the rolling-stock, but also prevents to a large degree the pounding action on the car-wheels from being transmitted so suddenly to the concrete portion of the ties, the result being that said ties will not become cracked or broken.

Referring to the drawings, A represents the tie as a whole, having, preferably, a rectangular base, the sides and ends tapering upwardly, so that the top has a somewhat less area than the base, thus increasing the bed or bearing-surface of the tie. The inclined sides and ends, either being regarded as a lateral surface, enable the tie to take hold of the ballast better than if they were vertical, because the ballast on this portion transmits its weight to the tie and locks same securely in place. Any movement of the tie will tend to lock it beneath the ballast, the bottom edge acting like a plow-point or a cultivator-tooth. If

preferred, only the sides or only the ends may be tapered, and the corners of the tie are preferably rounded.

The tie A is made, preferably, of crushed slag, cement, concrete, or other plastic material and has embedded in it at its formation the plate B, made, preferably, of steel. This plate has a number of holes b through it, so that the concrete will run through them and lock the plate tightly in place within the concrete and unite the concrete together along the plane occupied by the plate. If the holes were not made, the portions of the concrete on opposite sides of the plate would have a large area entirely separated, and there would thus be lines and planes of weakness next to the plate, where the concrete might become broken; but when the holes are made the concrete binds together through the holes a large portion of the said lines and planes and becomes one solid mass.

The steel channel-plate B extends nearly the full length of the tie and has downwardly-bent lateral portions or flanges b', provided with outwardly-extending flanges or feet b''. The flanges b' of the plate B are provided with holes b. The flanges b' and b'' stiffen the plate against movement in the tie and also provide a series of holes B in a plurality of planes, so that the strain on one portion of the plate will not be transmitted so largely to all other parts.

Riveted to or otherwise secured to the channel-plate B are angle-plates G, each having a vertical portion or tongue standing up parallel with the rail E and slightly above the top of the rail-flange.

Lying in the concrete tie and flush with its upper surface is a steel plate C, which extends from one angle-plate G on one side of the rail to another plate G on the opposite side of the rail. Bolts H are passed up through the ends of the plate C and have their heads H' locked beneath the same, as shown in Figs. 2 and 3.

Seated on the plate C is a compressed cork cushion or plate F, covered and protected with flanged steel plate on which tie rail E lies. The cushion gives elasticity or resiliency to the solid tie construction and protects same.

against sudden strokes, such as are given to rails by the drive-wheels of locomotives or heavy-loaded cars, and makes the train less noisy and to a large degree prevents injury to the trucks or rolling-stock.

Strung on each bolt H is a soft-steel clip or plate J, having one end on the upper end of an angle-plate G and the other end on the bottom flange of the rail. A nut on each bolt 10 H is screwed down on each clip to hold the rail securely on the tie.

The concrete we prefer to use is made of crushed slag, sand, and cement; but we do not desire to be limited to this composition, as 15 other plastic hardening compositions may be used.

Having described our invention, we claim—

1. In a railway-tie, a plastic material having 20 embedded therein a perforated U-shaped plate of metal extending longitudinally of the tie continuously between the rails, the sides of the U-shaped plate extending downwardly.

2. In a railway-tie, a plastic material having embedded therein a perforated U-shaped plate of metal extending longitudinally of the tie 25 continuously between the rails, the sides of the U-shaped plate extending downwardly and a flange on each of said sides.

3. In a railway-tie, a plastic material having embedded therein a metal plate, upstanding 30 tongues borne in pairs on the plate, a metal bed-plate between each pair of tongues, an elastic cushion covered with steel-flanged cap-plate on the bed-plate, clips each bearing on a rail-flange and one of said tongues, bolts se- 35 cured by said bed-plate, and means on the bolts for holding the clips in place.

Signed at Pittsburg, Pennsylvania, this 3d day of June, 1903.

LOUIS BEEZER,
MICHAEL J. BEEZER.
